Des. 208,874
Patented Oct. 10, 1967

208,874

ICE CRACKER OR SIMILAR ARTICLE

Samuel D. Sacks, 1633 E. 4th St.,
Brooklyn, N.Y. 11230

Filed July 11, 1966, Ser. No. 3,012

Term of patent 14 years

(Cl. D44—29)

FIGURE 1 is a front elevational view of an ice cracker or similar article embodying my new design,

FIG. 2 is a side elevational view thereof,

FIG. 3 is a top plan view thereof, and

FIG. 4 is a bottom plan view thereof.

I claim:

The ornamental design for an ice cracker or similar article, substantially as shown.
